Inventor:

Michael Hoffman Wilson,
by his attorney,
Charles H. Searle,

UNITED STATES PATENT OFFICE.

MICHAEL HOFFMAN WILSON, OF BROOKLYN, NEW YORK.

BARBER'S POLE.

SPECIFICATION forming part of Letters Patent No. 354,961, dated December 28, 1886.

Application filed December 29, 1885. Serial No. 187,017. (No model.)

To all whom it may concern:

Be it known that I, MICHAEL HOFFMAN WILSON, a citizen of the United States, and a resident of Brooklyn, in the county of Kings 5 and State of New York, have invented a certain new and useful Improvement in Barbers' Poles, of which the following is a specification.

Poles having spiral bands painted or otherwise produced on the surface have long been 10 known as the arbitrary sign of the barber.

My invention consists in rotating the pole on its longitudinal axis, which motion will cause the spiral bands to appear to move longitudinally on the pole, each band closely following 15 its predecessor, and serve to attract the attention of the passer-by. I mount the pole with freedom to turn with little friction, and provide clock-work or other light motor for imparting the required rotation.

20 The accompanying drawings form a part of this specification, and represent what I consider the best means of carrying out the invention.

Figure 1 is an elevation, partly in vertical 25 section. Fig. 2 is a plan view of a portion detached.

Similar letters of reference indicate corresponding parts in both the figures.

I will describe the invention as applied to 30 what is known as a "box-pole."

A is the base or box, having a horizontal partition or brace, A², on which is mounted a step, a², and guide A⁴. On the under side of the top board, A', is fastened an anti-friction 35 bearing, A⁵, having rollers a⁶.

B is the pole, of any ordinary or suitable design, having at the lower end a stud or shaft, B', firmly fixed in the line of its longitudinal axis. This shaft extends downwardly through 40 the top board, A', between the anti-friction rollers a⁶, through the guide A⁴, and into the step a². Near the lower end is fixed a pinion, B², which is engaged by a spur-wheel, C, driven through a train of gearing (not shown) 45 by a spring, D, which is wound up by applying a properly-formed key to the squared end of the shaft E.

To prevent access of water to the interior of the box, I provide a collar, a', of sheet metal, 50 fastened to the upper face of the top board,

loosely encircling the lower end of the pole and extending a few inches upward. Over this collar, and fastened to the pole, is a circular apron, b', extending downwardly outside of the upright portion of a' far enough to effect- 55 ually shed any water which may run down the pole on the upper surface of the box, whence it will find its way to the ground.

Modifications may be made without departing from the principle or sacrificing the advantages of the invention.

The invention may be applied to other forms of barbers' poles besides the box-pole shown.

Other motors than clock-work may be em- 65 ployed to give the motion.

I can dispense with the anti-friction bearing A⁵ and depend upon the hole in the top board to guide the shaft B'.

It will be understood that the pole may be 70 painted with any combination of colors. A band or series of bands may be made to appear to run in the opposite direction.

The bands may be replaced by other devices, as stars arranged spirally. Plain rings 75 or horizontal bands may be painted at intervals.

I am aware that show-stands for shop-windows have been made to revolve by clock mechanism, and such devices are not sought 80 to be covered in this application. In my invention the peculiar configuration of the ornamentation affords a peculiarly attractive appearance to the sign.

Having thus described my invention, what I 85 claim is—

A barber's pole or sign mounted with freedom to revolve on its axis, in combination with a motor for imparting a revolving motion thereto, substantially as and for the purposes herein specified.

In testimony that I claim the foregoing as my invention I have signed my name, in presence of two witnesses, this 28th day of December, 1885.

MICHAEL HOFFMAN WILSON.
